(57) **CLAIM**

The ornamental design for a portion of a display screen with icon, as shown and described.

DESCRIPTION

The patent file contains at least one drawing executed in color. Copies of this patent with a color drawing will be provided by the Office upon request and payment of the necessary fee.

FIG. 1 is a front view of a portion of a display screen with icon according to a first embodiment of our design; and, FIG. 2 is a front view of a portion of a display screen with icon according to a second embodiment of our design.

The broken line showing of a portion of the display screen with icon in all views forms no part of the claimed design.
